UNITED STATES PATENT OFFICE

153,210

DESIGN FOR A CLOTHES WRINGER

Vernon E. Dunn, Alliance, Ohio, assignor to Appliance Manufacturing Company, Alliance, Ohio, a corporation of Ohio

Application November 2, 1948, Serial No. 149,437

Term of patent 7 years

(Cl. D49—1)

To all whom it may concern:

Be it known that I, Vernon E. Dunn, a citizen of the United States, residing at Alliance, in the county of Stark and State of Ohio, have invented a new, original, and ornamental Design for a Clothes Wringer, of which the following is a specification, reference being had to the accompanying drawing, forming part thereof.

Fig. 1 is a front elevational view of a clothes wringer, showing my new design.

Fig. 2 is a top plan view thereof, the dotted line wringer portion being fragmented for convenience of illustration.

Fig. 3 is a left hand end view of Fig. 1, the dotted line wringer portion being omitted for convenience of illustration.

The dominant feature resides in the portions shown in full lines in the drawings.

I claim:

The ornamental design for a clothes wringer, substantially as shown and described.

VERNON E. DUNN.
